(57) **CLAIM**

The ornamental design for a soft sided rechargeable electric cigar, as shown and described.

DESCRIPTION

FIG. 1 is a top perspective view for a soft sided rechargeable electric cigar showing my new design;

FIG. 2 is a front side view thereof;

FIG. 3 is a back side view thereof;

FIG. 4 is a left side view thereof;

FIG. 5 is a right side view thereof;

FIG. 6 is a top side view thereof; and

FIG. 7 is a bottom view thereof; and,

FIG. 8 is an exploded view thereof, shown with the top and bottom housing separated.
